UNITED STATES PATENT OFFICE.

EMIL BOMMER, OF NEW YORK, N. Y.

SPRING-HINGE FOR DOORS.

1,131,659.

Specification of Letters Patent.

Patented Mar. 16, 1915.

Application filed April 15, 1913, Serial No. 761,139. Renewed July 15, 1914. Serial No. 851,226.

To all whom it may concern:

Be it known that I, EMIL BOMMER, a citizen of the United States of America, residing in New York, in the borough of Brooklyn, county of Kings, and State of New York, have invented certain new and useful Improvements in Spring-Hinges for Doors, of which the following is a specification.

This invention relates to certain improvements in the spring-hinge for doors for which Letters Patent were granted to me heretofore numbered 825,104 and dated July 3d, 1906 and by which the construction of the same is simplified and rendered more reliable and effective, and for this purpose the invention consists of a spring-hinge which will be fully described hereinafter and finally pointed out in the claims.

In the accompanying drawing, Figure 1 represents a side-elevation of a door with my improved spring-hinge shown in position at the lower corner thereof, Fig. 2 is a horizontal section on line 2, 2, Fig. 3, drawn on a larger scale, Fig. 3 is a vertical longitudinal section through the spring-hinge and the stationary floor-plate of the same, Fig. 4 is a horizontal section on line 4, 4, Fig. 3, Fig. 5 is a vertical transverse section on line 5, 5, Fig. 3, and Fig. 6 is a detail of the upper end of the pintle, showing the guide-grooves on the same.

Similar letters of reference indicate corresponding parts throughout the different figures of the drawing.

Referring to the drawing, D represents a swing-door and D¹ the casing of the same. The lower rear-corner of the door is provided with a mortise of sufficient size for inserting a spring-hinge therein which corresponds in size and strength to the size and weight of the door. Below the spring-hinge, and axially in line with the pintle P of the same, is arranged a floor-plate B, which is attached by means of fastening screws b to the floor. The floor-plate B is provided with a tapering socket b¹ of square cross-section for receiving the lower corresponding-tapered and squared end p of the pintle P and holding it thereby in a non-rotatable position. On the lower end of the pintle P is journaled an oblong frame

F which is provided at its upper end with a hole into which, and into a socket in the upper end of the pintle P is inserted an auxiliary smaller pintle p¹ by which the connection of the pintle with the hinge-frame F of the spring-hinge is made. The hinge-frame F is provided with a vertical extension f at its upper end and with a horizontal extension f¹ at its lower end, which ends are attached to the door by means of fastening screws f², as shown in Fig. 3. The hinge-frame F is preferably made of cast metal and covered at its outer vertical portion by a sheet-metal facing f³ which is lapped inwardly over the edges of the outer wall of the frame, as shown in Figs. 2 and 3. The spring-hinge is inclosed by sheet-metal side-plates f⁴ which are attached to the lower corner of the door and which serve to protect the interior parts of the spring-hinge against the ingress of dust.

On the pintle P is arranged at the interior of the frame F a coil-spring S of sufficient power to return the door from its open into its closed position. The lower end of the coil-spring S is bent downwardly and inserted into a recess h⁷ of the lower spring-holder H, while the upper end of the coil-spring S is provided with an upwardly-bent end which is inserted into a recess h⁸ of the upper spring-holder H¹ in the usual manner. The lower spring-holder H is provided with a lug h⁵ at its circumference and a pin h⁶ at its interior. The upper spring-holder H¹ is provided with radial holes h⁹ for inserting a tension-pin h by which the coil-spring S is set to tension in the usual manner. Above the upper spring-holder H¹ is arranged a tension-collar H² which has also a lug h² on its circumference and a pin h³ on its interior, said lug having a downwardly-extending stop h⁴ adapted to receive the recoil of the hinge-spring S upon the tension-pin h of the upper spring-holder H¹, after the spring is set to tension, and to transmit said recoil by the interior pins h⁵, h⁶ of the tension-collar H² and of the lower spring-holder H to the ends or stops p⁶ and p⁷ of horizontal guide-grooves p² and p³, which extend laterally from vertical guide-

grooves p^4 and p^5 on the pintle P, and hold said interior pins h^3 and h^4 in contact therewith in order to retain the door in its normally closed position and locate the lug h^5 of the lower spring-holder and the lug h^2 of the tension-collar in correct alinement with the cheeks c of the hinge-frame F, and, when the door is swung into open position in one or the other direction to again return the same into its normally closed position by the recoil of the hinge-spring S. The upper and lower ends of the pintle P are preferably made larger in diameter than the middle portion for arranging thereon the horizontal and vertical grooves p^2 , p^3 and p^4 , p^5 at the upper and lower ends of the same. The inwardly-extending pin h^3 of the tension-collar H^2 is adapted to travel in the horizontal groove p^2 of the upper enlarged portion of the pintle P, while the inwardly-extending pin h^4 of the lower spring-holder H is adapted to travel in the horizontal groove p^3 in the lower enlarged portion of the pintle P. The length of the horizontal grooves p^2 , p^3 is proportioned to the angle through which the door is desired to be opened, one horizontal groove extending in one, the other in the opposite direction from the vertical grooves so as to provide for the opening of the door in one of the opposite direction. The contact-faces of the lugs h^5 and h^2 on the spring-holder H and tension-collar H^2 are held at all times when the coil-spring S is under tension in correct position or vertical alinement with each other by the abutting of the interior pins h^3 and h^4 against the ends or stops p^6 and p^7 of the horizontal guide-grooves p^2 and p^3 . Between the upper horizontal portion of the hinge-frame F and the tension-collar H^2 is preferably interposed on the auxiliary pintle p^1 an antifriction-washer or ball-bearing α , which serves to take up the weight of the door upon the pintle and permit the easy and noiseless motion of the spring-hinge when opening or closing the door. The inner wall of the oblong hinge-frame F is provided near its upper and lower ends with projecting cheeks c, which are preferably made integral with the hinge-frame and arranged so as to be in the path of the exterior lugs h^5 and h^2 of the spring-holder H and tension collar H^2 , so that when the coil-spring S is under tension, the lower and upper cheeks c are in contact with the exterior lugs of the spring-holder and tension collar to hold the door in its normally closed position. For this purpose the projecting cheeks are preferably arranged at one side and the other of the vertical center-line of the inner vertical wall of the hinge-frame F. The tension of the coil-

spring increases as the door is opened in one or the other direction while on the release of the door the recoil of the spring returns the door to its normal, closed position, the interior pins h^3 and h^4 being again seated in the ends or stops p^6 and p^7 of the horizontal grooves p^2 and p^3 of the pintle P.

The parts of the spring-hinge can be readily assembled by first inserting the pintle through the lower journal of the hinge-frame and then placing successively, one after the other, the lower spring-holder, the coil-spring, the upper spring-holder, the tension collar, and the antifriction-bearing in position on the pintle, and then connecting the same by the auxiliary pintle into proper position in the hinge-frame, the vertical grooves of the pintle permitting the slipping in of the interior pins of the lower spring-holder and tension-collar. The hinge-frame is then attached to the lower corner of the door in the manner described. It will also be understood that the projections or cheeks c might be located on either one of the inner walls of the hinge-frame, or one cheek c might be located at the upper part of one of the inner walls of the hinge-frame, while the other cheek c may be located at the lower part of the other inner wall of the hinge-frame without changing the spirit or nature of this invention.

The advantages of the improved spring-hinge for doors are that by its construction the assembling of the parts is greatly simplified and that it forms a strong and effective hinge for returning the door into closed position after the same has been opened in one direction or the other.

One embodiment of my invention has been shown and described, but it is clear that changes may be made therein without departing from the spirit of my invention, as defined in the appended claims.

I claim:

1. In a spring-hinge for doors, the combination of a non-rotatable pintle secured to the floor, an oblong hinge-frame attached to the door and journaled on said pintle, said pintle being provided with enlarged upper and lower ends having horizontal guide-grooves, a lower spring-holder on said pintle provided with an interior pin engaging the lower guide-groove, an upper spring-holder having radial holes, a coil-spring engaging said spring-holders, a tension-collar adjacent to the upper spring-holder provided with an interior pin engaging the upper guide-groove of the pintle, an exterior lug on the lower spring-holder and on the tension-collar, the lug of the latter being extended over the upper spring-holder, a tension-pin inserted into one of the holes of the upper spring-holder and abutting against

the extension of the lug on the tension-collar, and cheeks on the inner wall of the hinge-frame adapted to engage either the lug on the lower spring-holder or the lug 5 on the tension-collar according as the door is moved in one or the other direction.

2. In a spring-hinge, the combination with a non-rotatable pintle secured to the floor, an oblong hinge-frame attached to the 10 door and journaled on said pintle, said pintle being provided with horizontal grooves and vertical guide-grooves connected therewith and with a socket in its upper end, an auxiliary pintle connecting 15 the upper end of the pintle with the upper end of the hinge-frame, a lower spring-holder on the pintle provided with an inwardly-projecting pin for engaging the lower grooves of the main-pintle, an upper 20 spring-holder, a coil-spring engaging said spring-holders, a tension-collar adjacent to the upper spring-holder provided with an inwardly-projecting pin for engaging the upper guide-grooves of the pintle, exterior 25 lugs on the lower spring-holder and tension-collar, the lug of the tension-collar being provided with a downwardly-extending stop, and a tension-pin inserted into holes of the upper spring-holder and engaging 30 the stop on the tension-collar, the auxiliary pintle being disconnectable from the upper portion of the hinge-frame and the upper end of the pintle, permitting the assembling 35 of the spring-holders, coil-spring and tension-collar on the pintle.

3. In a spring-hinge for doors, the combination of a non-rotatable pintle, an oblong hinge-frame journaled on said pintle being provided with a socket in its upper end, a 40 spring-holder at the lower end of the pintle, a spring-holder at the upper end of the pintle, a tension-collar above the upper spring-holder, a coil-spring engaging the lower and upper spring-holders, and an auxiliary pin- 45 tle connecting the upper end of the hinge-frame with the socketed upper end of the pintle.

4. In a spring-hinge for doors, the combination of a non-rotatable pintle, an oblong hinge-frame journaled on said pintle, said pintle being provided with horizontal guide-grooves and said hinge-frame being provided with stop-cheeks at its upper and lower ends, a lower spring-holder, an upper 50 spring-holder, a coil-spring connecting said spring-holders, a tension-collar above the upper spring-holder, interior pins on the lower spring-holder and tension-collar, exterior lugs on the same, the lug on the tension-collar extending over the upper spring-holder and engaged by the pin of the upper spring-holder by the recoil of the spring. 55

60

65

5. In a spring-hinge for doors, the combination of a non-rotatable pintle provided with horizontal guide-grooves, an oblong hinge-frame journaled on said pintle and the inner wall of which is provided with 70 stop-cheeks at the upper and lower ends, a lower spring-holder, an upper spring-holder, a coil-spring connecting said spring-holders, a tension-collar above the upper spring-holder, an interior pin on the lower 75 spring-holder and on the tension-collar, exterior lugs on the same, the lug of the tension-collar extending over the upper spring-holder, a tension-pin in the upper spring-holder abutting against the extension-lug of 80 the tension collar, the lugs on the lower spring-holder and upper tension-collar being in the path of the lower or upper cheek of the hinge-frame when the door is opened in one or the other direction, the length of 85 the horizontal grooves of the pintle determining the angular swing of the door.

6. In a spring-hinge for doors, the combination of a non-rotatable pintle having guide-grooves, spring-holders thereon, a 90 coil-spring for said spring-holders, a tension-collar, pins in the spring-holders and in the tension-collar, the interior pin of one of the spring-holders and of the tension-collar abutting against one end of the guide-grooves of the pintle when the door is in 95 closed position and the interior pin of the other tension-collar abutting against the opposite end of said grooves when the door is in fully opened position.

7. In a spring-hinge for doors, a non-rotatable pintle, horizontal guide-grooves on the ends of the pintle, vertical guide-grooves extending from the horizontal guide-grooves toward each other, the horizontal guide-grooves extending in opposite direction to 105 each other and determining by their length the angular swing of the door in one or the opposite direction.

8. In a spring-hinge for doors, the combination of a non-rotatable pintle having guide-grooves, spring-holders thereon, a tension-collar, pins in one of the spring-holders and in the tension-collar, and exterior lugs on one of the spring-holders and tension-collar, the lug of the tension-collar extending over the upper spring-holder and engaged by the pin of the upper spring-holder by the recoil of the spring.

9. In a spring-hinge for doors, the combination of a non-rotatable pintle having guide-grooves, a hinge-frame therefor, spring-holders thereon, a tension-collar, pins in one of the spring-holders and in the tension-collar, exterior lugs on one of the 115 spring-holders and tension-collar, and cheeks on the hinge-frame adapted to be engaged by said lugs by the recoil of the spring when the door is opened in one or the other direction.

10. In a spring-hinge for doors, the combination of a non-rotatable pintle, a hinge-frame journaled on said pintle and provided with a socket in its upper end, and an auxiliary pintle connecting the upper end of the hinge-frame with the socketed upper end of the pintle.

In testimony, that I claim the foregoing as my invention, I have signed my name in presence of two subscribing witnesses.

EMIL BOMMER.
